CARRYING CASE FOR BOWLING ACCESORIES OR THE LIKE

Robert C. Kelley, Muskegon, Mich., assignor to Brunswick Corporation, Chicago, Ill., a corporation of Delaware

Filed Nov. 13, 1963, Ser. No. 77,400

Term of patent 14 years

(Cl. D87—5)

FIGURE 1 is a rear elevational view of a carrying case for bowling accessories or the like, embodying my new design;

The side not shown is substantially identical to that shown.

The dominant features of the design are shown in full lines on the drawing.

I claim:

The ornamental design for a carrying case for bowling accessories or the like, as shown and described.
